POLISH ROD HANGER

Robert Claud Johnston, Longview, Tex.

Application April 25, 1936, Serial No. 76,488

9 Claims. (Cl. 24—263)

This invention relates to pump mechanism, and particularly pertains to a polish rod hanger.

In the operation of oil well pumping mechanism, which includes a polish rod extending into the well and driving means to reciprocate the same, it often occurs that due to inequality in pressures exerted upon the pump pistons or the rods, there is a tendency for the rod to rotate. This may unscrew the rod at some one of its joints, and if not may place an undesirable twisting strain upon the rods. It also often occurs that sand and other solid matter suspended in the liquid being pumped will accumulate within the pump cylinders. This accumulation "sands up" the cylinders so that the pump pistons may not move throughout their entire stroke. When the polish rod is being moved by driving mechanism positively connected therewith it will be evident that the stroke of the driving mechanism will remain constant while the possible movement of the polish rod is shortened. This will place undue strain upon the polish rod tending to produce crystallization at a possible "parting" of the rod. It is the principal object of the present invention to provide a polish rod hanger and grip which is interposed between the polish rod and its driving mechanism, and which acts to adjust itself automatically to conditions existing in the well whereby the force might be exerted to rotate the polish rod or to shorten its stroke.

The present invention contemplates the provision of a polish rod hanger including a housing in which a freely rotatable sleeve is mounted and within which sleeve the polish rod slips are carried to positively grip the rod on the upstroke of the driving mechanism and to, if necessary, release the rod and regrip it at the end of its down stroke.

The invention is illustrated by way of example in the accompanying drawing in which:

Figure 1 is a view in central vertical section through the polish rod hanger with which the present invention is concerned.

Fig. 2 is a view in plan showing the rod hanger. Fig. 3 is a view in side elevation showing the rod hanger and indicates the pivotal connection of the hanger straps.

Referring more particularly to the drawing, 10 indicates the outer cylindrical housing of a rod hanger which carries trunnions 11 and 12. These trunnions extend from diametrically opposite sides of the housing and receive the bearing ends of straps 13 and 14. It is to be understood that these straps are a part of the usual reins by which a driving connection is made with a walk-

ing beam or other member which will produce a reciprocating motion of the polish rod. A central bore 15 is formed within the housing 10 and at its lower end terminates with an inturned flange 16 having a central bore 17 therethrough of reduced diameter. Resting upon the face 18 of the flange is a thrust ball race 19 having a downwardly extending lip 20 which fits within the bore 17 and thus centers the ball race. A series of thrust bearing balls 21 rest upon the race and are engaged by a race face 22 formed around the body of a slip sleeve 23. The slip sleeve has an enlarged cylindrical body portion which has a rotating bit within the bore 15 of the housing 10 and has a reduced cylindrical portion 24 which extends down into the central bore 25 of the ball race 19. The sleeve 23 is formed with a central tapered bore 26 which tapers downwardly and inwardly and which at its upper end terminates with a cylindrical counterbore 27. A plurality of polish rod slips 28 extend through the bore of the sleeve 23. These slips are tapered to conform to the taper of the bore 26 and will thus move to contracting positions as they are forced downwardly into the tapered bore. The upper ends of the slips are formed with cylindrical portions 30 here shown as extending through a housing top plate 31. The cylindrical portion 30 represents a reduced diameter as compared to the large diameter of the upper end of the tapered portion of the slips and thus accommodates a friction washer 32 which is interposed between the cover plate 31 and a shoulder 33 on the slips. The cover plate is secured in position by cap screws 34. The slips are formed with arcuate inner faces 29 having the usual serrations thereon to grip a cylindrical member on the upstroke and in the present instance to grip a polish rod and lift it incident to a pumping operation.

In operation of the present invention the device is assembled as shown in Fig. 1. It will be understood that a polish rod extends upwardly through the central opening defined by the arcuate slip faces 29 and that the upper end of the polish rod is free, save when it is gripped by the serrated teeth on the slips. During pumping the strap arms 13 and 14 will be moved upwardly and downwardly by a suitable pump driving mechanism and when all conditions of pressure are uniform the polish rod hanger and the polish rod 35 will move in unison. In the event that force is exerted tending to set up torsion in the polish rod, the polish rod, the slips 28, and the sleeve 23 will rotate on the ball bearings 21. It is not desirable, however, for this rotation to take

place without resistance since in that case the rods might be freely rotating at all times. It is for that reason that the friction washer 32 is provided. This washer is of a thickness to be 5 clamped between the shoulder 33 and the cover plate 31 to resist slight twisting strains and to permit excessive twisting strains to overcome the friction between the parts, so that the polish rod may rotate without resisting the rotating force 10 sufficiently to impose an undue strain upon the rod or to unscrew any of the joints. In the event that the pump cylinder becomes "sanded up" so that the pistons cannot move down to the desired length of stroke for which they were designed and 15 are driven it will be evident that at the point where resistance to downward movement of the polish rod 35 is sufficient to prevent downward movement of the rod, the rod hanger will be automatically released from the slips and the slips 20 will slide downwardly to the full length of the power stroke of the pumping mechanism. It will be evident that if the friction washer 32 is made of non-metallic material having some yieldability, such for example as rubber or fibre, the washer 25 will yieldably hold the slips in their lowermost position so that as soon as the lower end of the stroke of the pump driving mechanism is reached and a reverse stroke is initiated the slips will grip the rod and lift it in unison therewith. This action 30 will therefore automatically permit readjustment of the polish rod with rod hanger and pump mechanism so that as the pump cylinder accumulates material resisting the down stroke of the polish rod no damage will be done to the pump or the rod.

It will thus be seen that the present invention while decidedly simple in its construction, provides a positive grip for a polish rod of a pump on its lifting stroke, and permits free adjustment 40 of the rod when undue torsional or thrust strains are imposed upon it.

While I have shown the preferred form of my invention as now known to me, it will be understood that various changes might be made 45 in the combination, construction, and arrangement of parts, by those skilled in the art, without departing from the spirit of the invention as claimed.

Having thus described my invention, what I 50 claim and desire to secure by Letters Patent is:

1. In combination with a pump polish rod, a rod hanger having reciprocating movement, a housing, separate means engaging the polish rod on the upstroke of said hanger to cause the rod 55 and the hanger to move in unison, said means automatically releasing the rod when the down stroke of the rod is less than the down stroke of the hanger, and a bearing structure carrying the rod engaging means and supporting the same for rotational movement relative to the housing whereby rotation of the polish rod with 60 relation to the hanger may take place.
2. In combination with a pump polish rod, a rod hanger having reciprocating movement, means engaging the polish rod on the upstroke of said hanger to cause the rod and the hanger to move in unison, said means automatically releasing the rod when the down stroke of the rod is less than the down stroke of the hanger, a bearing structure for rotatably supporting the rod engaging means within the hanger and permitting rotation of the polish rod with relation 65 to the hanger, and means resisting said rotation.
3. In combination with a pump polish rod, a hanger by which it is operatively connected to 70

a pumping mechanism, said hanger including a housing, slip means therein for gripping the rod, and a bearing structure rotatably supporting the slip means within the housing whereby relative rotation of the slip means with relation to the 5 housing and in either direction may take place.

4. In combination with a pump polish rod, a hanger by which it is operatively connected to a pumping mechanism, said hanger including a housing, slip means therein for gripping the rod, 10 a bearing structure supporting the slip means within the housing for permitting relative rotation of the slip means with relation to the housing and in either direction, and means frictionally resisting said rotation.

5. In combination with a pump polish rod, a hanger by which it is operatively connected to a pumping mechanism, said hanger including a housing, slip means therein for gripping the rod, a bearing structure supporting the slip 20 means within the housing for permitting relative rotation of the slip means with relation to the housing and in either direction, means interposed between said slip means and the housing for frictionally resisting said rotation, and 25 the bearing structure carrying anti-friction bearing means interposed between the housing and the rod gripping means.

6. A polish rod hanger comprising a housing, trunnions upon opposite sides thereof to receive 30 a beam hanger, a slip sleeve within said housing, thrust bearing means within the housing and upon which the slip sleeve seats, and a cover plate at the top of the housing for retaining the sleeve therein.

7. A polish rod hanger comprising a housing, trunnions upon opposite sides thereof to receive a beam hanger, a slip sleeve within said housing, thrust bearing means within the housing and upon which the slip sleeve seats, a cover plate 40 at the top of the housing for retaining the sleeve therein, and friction means interposed between the sleeve and the cover plate tending to resist relative rotation of the sleeve and the housing.

8. A polish rod hanger comprising a housing, 45 trunnions upon opposite sides thereof to receive a beam hanger, a slip sleeve within said housing, thrust bearing means within the housing and upon which the slip sleeve seats, a cover plate at the top of the housing for retaining the sleeve 50 therein, friction means interposed between the sleeve and the cover plate tending to resist relative rotation of the sleeve and the housing, and a plurality of slips mounted within the sleeve and yieldably supported in a gripping 55 position.

9. A polish rod hanger, a housing formed as a part of said polish rod hanger, trunnions carried thereby to receive a beam hanger, a slip sleeve rotatably mounted within the polish rod 60 hanger, a thrust bearing upon which the slip sleeve is rotatably supported, said slip sleeve being formed with a central downwardly and inwardly tapered bore, a plurality of slips having outer tapered faces to seat within the tapered bore of the slip sleeve and having inner serrated faces to engage a polish rod extending therethrough, an upper shoulder formed on each of said slips, a non-metallic yieldable member mounted on said shoulder and embracing the 65 upper ends of the slips, and a plate secured to the polish rod hanger housing and bearing against said non-metallic member.
